UNITED STATES PATENT OFFICE.

EDWARD BOEKENKAMP, OF ST. LOUIS, MISSOURI, ASSIGNEE TO AMERICAN STOVE COMPANY, OF ST. LOUIS, MISSOURI, A CORPORATION OF NEW JERSEY.

KNOCKDOWN OVEN.

1,143,028.

Specification of Letters Patent. Patented June 15, 1915.

Application filed February 23, 1915. Serial No. 10,105.

To all whom it may concern:

Be it known that I, EDWARD BOEKENKAMP, a citizen of the United States, residing in the city of St. Louis and State of Missouri, have invented certain new and useful Improvements in Knockdown Ovens, of which the following is a specification, reference being had therein to the accompanying drawing.

10 My invention relates to improvements in knock-down ovens the primary object of which is to devise an oven of this character which may be easily and quickly put together, and when in its assembled position, 15 be perfectly solid and rigid and be as well made for practical use as though it were assembled by the manufacturer.

Another object of the present improvement is to devise an oven of this character 20 which will occupy a small amount of space and can be readily packed when in its knock-down form.

A still further object of the present improvement is to construct an oven of this 25 kind in which the means for uniting the several sections of the oven are hidden from view.

Other objects and advantages of the present improvement will be set forth in the 30 following description and drawings in which,

Figure 1 is a perspective view of the oven in its assembled form showing the door of the oven open and the last portion of it being put in place. Fig. 2 is a perspective view of the parts of the oven in disassembled relation and stacked upon each other and ready for boxing and shipping. Fig. 3 is a perspective view showing the first step 40 of assembling the oven. Fig. 4 is a perspective view of the next step in assembling the oven and showing it ready to receive the front and back. Fig. 5 is a perspective view of the oven showing all of the parts in place 45 and the front and back partly fitted and showing the method of locking the assembling strips. Fig. 6 is a fragmental perspective view of a corner of the oven showing two of the members in position to receive a locking strip. Fig. 7 is a fragmental sectional view of the same portion of the oven shown in Fig. 6, and showing the attaching strip applied to the meeting of two of the sides of the oven for holding it to-

gether. Fig. 8 is a perspective view of one of the attaching strips.

My improved oven consists of six sections or parts and comprises a top 1, bottom 2, two sides 3 and 4 respectively, and a front 5 and back 6. The top, two sides, and back of the oven are provided with a corrugated spaced lining 7, which provides means for insulating the interior of the oven from the atmosphere and retaining the heat within the oven. The top 1, bottom 2, and sides 3 and 4, are all of rectangular shape, two end edges of which are provided with outwardly extending portions 8 which are bent and doubled back upon themselves at 9 to form a portion 10 which extends at an acute angle to the portion 8. The portions 8 of these parts extend a distance beyond the corrugated lining 7, and when the two edges of either of these parts are placed together so that the corners 9 will be abutting, a rectangular space 11 is left. The members 10 carried by two edges of the top, bottom and two sides respectively coöperate with a locking strip which provides means for uniting these sections together and holding them in their united position. The locking strip consists of an elongated member 12 comprising a body portion 13 and two portions 14 extending at acute angles thereto and made integral with the body portion 13. The body portion 13 extends a short distance above and below the portions 14 to provide tongues 15, the purpose of which will be hereinafter set forth. When the top 1 and a side 3 are placed in the position shown in Fig. 3 (which is the first step of assembling the oven) the members 10 occupy the positions relative to each other shown in Fig. 6. A locking strip, of which there are four, is slipped down over the members 10 so that the members 14 of the strip are adjacent the members 10, and the body portion 13 of the strip is at an angle thereto. The position of the locking strip relative to the members 10 is shown in Fig. 7.

In assembling the oven, the top 1 and one side 3 are placed in the position shown in Fig. 3, and a locking strip inserted through their corners as has been heretofore described. The other side and bottom are then placed in the positions shown in Fig. 4 so that the edges provided with annular extensions 10 are in the relation to each

other as shown in Fig. 6. Locking strips 12 are then passed through the corners of the other side and bottom so as to lock these four members together as is shown in Fig. 4.

5 After the top, bottom and two sides have been united and the locking strips pushed down so that only the tongues 15 extend above and below the four united sections, the front and back are next applied. The 10 front consists of a body portion 16 provided with downwardly extending flanges 17. The corners of the body portion 16 are provided with slots 18 arranged obliquely across the corners. These slots are arranged 15 in a position to receive the extending tongues 15 of the locking strip when the body portion 16 of the front is placed upon the edges of the top, bottom and two sides so that the flanges 17 of the top may engage 20 the sides of the top, bottom and two sides as is readily understood.

The back 6 is made in a similar manner to the front comprising a body portion provided with depending flanges 19 and slots 25 which are adapted to receive the extending tongues of the locking strips 12. When the front and back have been placed upon the top, bottom and sides so that the tongues 15 protrude through the openings 18 made in 30 the body portion of the front and back, the tongues are then bent down upon the body portion of the front and back, as is shown in Fig. 1. The bending of the tongues both secures the front and back to the top, bottom and two sides, and at the same time locks the top, bottom and two sides together so that they cannot move longitudinally on the locking strips.

The front 5 of the oven is provided with 40 a door 20 mounted upon suitable hinges 21 and provided with the usual form of handles and catches 22. The bottom 2 of the oven is also provided with the usual opening 23 which fits over the gas burners. The 45 lining of the two sides of the oven 3 and 4, are provided with outwardly extending flanges 28 which are adapted to receive a baffle plate 24, and two shelves 25 and 26 which are all of usual construction. The 50 two top edges of the sides 3 and 4, are also provided with handles 27 which provide means for lifting the oven about.

The collapsing of the oven is done in the 55 inverse manner to the way of assembling it, as has been heretofore described, and when in its collapsed form, the parts of the oven are placed one upon the other in the following order: Front and back are first placed one on top of the other having their linings 60 adjacent each other; the baffle plate 24 and shelves 25 and 26 are next placed upon the front; on top of the shelves 25 and 26 are placed the top and bottom one upon the other; next in order are the two sides which 65 are placed one upon the other with their

corrugated linings abutting each other. When the parts of the oven are stacked in this manner, they are found to occupy a very small amount of space so that they may be shipped in relatively small boxes.

70 From the foregoing description it is apparent that I have evolved a knock-down oven of simple construction which may be quickly and easily assembled. It is also apparent that I have constructed an oven 75 which may be assembled and held in its assembled position by means of four locking strips which hold all of the parts of the oven together, and at the same time are invisible from the outside of the oven.

Having thus fully described my invention what I claim and desire to secure by Letters Patent is:

1. A knock-down oven comprising a plurality of sections adapted to fit together, some of the said sections provided with flanges at their abutting corners, strips each one fitting over the flanges carried by the sections, said strips provided with extending tongues, the other sections provided with 90 openings in the corners thereof to receive the tongues of the strips, the parts arranged as and for the purpose described.

2. A knock-down oven comprising a plurality of sections adapted to fit together, 95 some of the said sections having flanges on their corners, locking strips engaging the said flanges, means carried by the said strips for holding the other sections of the oven to the sections having flanges at their corners.

3. A knock-down oven comprising six sections adapted to fit together, four of the said sections provided with flanges at their abutting corners, four strips each one fitting over the flanges carried by the sections, said strips provided with extending tongues, two sections provided with openings in the corners thereof to receive the tongues of the strips, the parts arranged as and for the purpose 110 described.

4. A knock-down oven comprising a plurality of sections adapted to fit together, two edges of some of the said sections provided with outwardly extending portions, said outwardly extending portions bent back upon themselves to form an acute angle, the said edges of each section arranged to meet each other at right angles, a locking strip comprising a body portion having two members integral therewith and arranged converging thereto, said strip engaging the doubled portions of the extending edges of the sections, said strips provided with tongues at their upper and lower ends, the other sections of the oven provided with openings in their body portions to receive the extending tongues of the said strips.

5. A knock-down oven comprising six sections adapted to fit together, two edges of 120

four of the said sections provided with outwardly extending flanges of triangular shape, the said triangular flanges of the sections arranged adjacent each other, locking 5 strips of a shape to fit over the triangular flanges of the said sections, said strips provided with tongues at their ends, the other two members provided with openings in their corners to receive the tongues bent 10 back upon the body portion of the two last-mentioned sections.

6. A knock-down oven comprising six rectangular sections, four of the said sections having their edges arranged at right angles to each other, each of the abutting edges of the said sections provided with an inwardly extending flange at an angle to the body portion of each section, locking strips of a length greater than the width of the four 15 sections, the said locking strips comprising a body portion and two flanges arranged at an angle thereto, the said flanges of a length equal to the length of the abutting edges of the four sections, whereby the body portion 20 of the strips will project above and below the edges of the four sections, the said locking strip fitting over the inwardly bent flanges of the edges of the sections, whereby the flanges of the strip are adjacent the flanges of the edges, the other two sections 25 provided with oblique openings at their corners adapted to receive the extending body portions of the locking strips, the said extending portions bent back upon the body portion 30 of the two last-mentioned sections.

7. A knock-down oven comprising six rectangular sections, four of the said sections provided with linings spaced apart from the body portion, the edges of the four sections 40 arranged at right angles to each other, two opposite edges of the four sections provided with flanges extending beyond the lining thereof, the said outwardly extending flanges provided with an inwardly bent portion at 45 an angle thereto, whereby when the said sections are arranged so that their corners are at right angles a space will be left between the abutting edges of the lining, locking strips comprising a body portion of a length 50 greater than the width of the four sections, said body portion having two flanges ar-

ranged at converging angles thereto, said flanges of a length equal to the width of the four sections, said locking strips slid down over the inner bent portions of the 55 flanges carried by the four sections, whereby the said flanges will be adjacent the inwardly bent portions of the flanges of the sections and be invisible from either the inside or outside of the said sections, two other 60 sections comprising a body portion having downwardly extending flanges upon all four edges, said body portions having oblique slots in their corners to receive the extending portions of the locking strips, downwardly 65 extending edges of the said sections engaging the sides of the first four mentioned sections, the extending portions of the locking strips bent down upon the body portion of the last two-mentioned sections. 70

8. A knock-down oven comprising a plurality of sections adapted to fit together, members engaging the adjacent edges of some of the sections for holding them together, said members providing portions engaging the corners of the other sections having means for locking all the sections together. 75

9. A knock-down oven comprising a plurality of sections adapted to fit together 80 members engaging the adjacent edges of some of the sections for holding them together, said members having portions extending through the body portion of the other sections and providing means for holding 85 all of the sections together.

10. A knock-down oven comprising a plurality of sections adapted to fit together, members engaging the adjacent edges of some of the sections for holding them together, said members having portions extending through the body portion of the other sections adjacent their corners providing means for holding all of the sections together. 90

In testimony whereof I hereunto affix my signature in the presence of two witnesses.
